UNITED STATES PATENT OFFICE

2,570,162

REFRIGERATOR CAR

Robert Kent Schwebs, Appleton, Wis.

Application January 12, 1946, Serial No. 640,873

1 Claim. (Cl. 98—6)

1

This invention appertains to railroad rolling stock and more particularly to refrigerators cars, and is an improvement over my prior Patents 2,136,894; 2,159,406; 2,203,180; and 2,314,463, issued to me, respectively, November 15, 1938; May 23, 1939; June 4, 1940; and March 23, 1943.

One of the primary objects of my invention is to provide a novel means for driving the air circulating fans by turbines driven from oil or any other preferred type of liquid, placed under pressure by pumps arranged at advantageous places on the car and operated from the motion of the car body and trucks.

Another salient object of my invention is to provide novel means for operating the pumps from an axle of a car or from the motion developed between cars or between car bodies and their trucks, whereby the use of extraneous driving motors is eliminated.

A further important object of my invention is to provide novel means for arranging the fluid driven turbines relative to the air circulating fans, whereby not only will the fans be efficiently operated for circulating the air through the bunkers and body, but whereby a minimum amount of space will be taken up within the car body.

A still further object of my invention is to provide novel means for operating air circulating fans in a refrigerator car which will be durable and efficient in use, one that will be simple and easy to manufacture and one which can be placed upon the market and incorporated with a standard refrigerator car at a low cost.

With these and other objects in view, the invention consists in the novel construction, arrangement and formation of parts, as will be hereinafter more specifically described, claimed and illustrated in the accompanying drawings, in which drawings:

Figure 1 is a fragmentary longitudinal sectional view through a refrigerator car showing my invention incorporated therewith, the section being taken substantially on the line 1—1 of Figure 2, looking in the direction of the arrows.

Figure 2 is a transverse sectional view taken on the line 2—2 of Figure 1, looking in the direction of the arrows, illustrating one preferred method of operating the air circulating fans from turbines located exteriorly of the cars.

Figure 3 is a section similar to Figure 2 but taken on the line 3—3 of Figure 1, looking in the direction of the arrows.

Figure 4 is a detail fragmentary side elevational view showing one method for attaching

2

one of the air driven turbines to the side of a car, the view being partly broken away and in section to illustrate structural detail.

Figure 5 is an enlarged fragmentary transverse sectional view through a refrigerator car showing another form for driving a pair of air circulating fans from a single line shaft.

Figure 6 is an enlarged fragmentary transverse sectional view taken on the line 6—6 of Figure 5, looking in the direction of the arrows, showing one of the air circulating fans.

Figure 7 is a view similar to Figure 1, but showing the fans so arranged as to circulate the air in a different direction from that shown in Figure 1.

Figure 8 is a fragmentary detail transverse sectional view through a car illustrating means for operating the fluid circulating pump from the side sway motion of the car body and trucks relative to one another while the car is in transit.

Figure 9 is a view similar to Figure 8, but showing a modified form or means for operating the circulating pump from the motion developed between parts of a car truck.

Referring to the drawings in detail, wherein similar reference characters designate corresponding parts throughout the several views, the letter C generally indicates a refrigerator freight car and the same includes the customary insulated body 10, having formed at each end thereof, by transverse partitions 11, bunkers 12 for the reception of ice 13. The ice rests on a grating 14 arranged above the level of the car floor. The body 10 of the car is, likewise, provided with a suitable perforated false bottom 15, on which the foodstuffs to be shipped are placed.

The car body 10 is supported in the usual or customary manner upon car trucks 16. The car trucks 16 include side frames 17 and 18 supporting at their ends, pedestals 19 for the journal boxes 20. These journal boxes 20 rotatably receive the wheel axles 21 on which are mounted the car wheels 22.

Arranged between the journal boxes is a transversely extending bolster 23, the terminals of which extend through the side frames 17 and 18. This bolster 23 is resiliently supported by coil springs 24 which rest upon a supporting plank 25 carried by the side frames. The upper end of the bolster 23 carries the center plate 26 for the center bolt (not shown) and the upper bolster 27 rests upon the center plate and is connected therewith by said center pivot bolt. The upper bolster 27 is rigidly secured to the bottom of the car body 10.

In accordance with my invention, I arrange above the partition 11, one or more air circulating fans 30. In the present instance I have shown two fans directly above the partition and firmly secured to the roof of the car 10. Similar fans 31 are secured to the roof of the car in rear of the partition 11 and at the end of the car above the bunkers. Like air circulating fans 32 are arranged below the bunkers and below the grating 14, at the ends of the car. Each of these air circulating fans includes a casing 33 having an outlet 34 and an intake 35. Rotatably mounted within each casing is the propeller or fan 36, itself.

The inlets 35 for the fans 30 extend into the bunkers for drawing air therefrom and the outlets 34 extend into the car body adjacent to the roof for forcing or blowing air into the car body above the partitions.

The intakes 35 for the fans 31 extend downwardly into the bunkers and suck cool air up from the ice. The outlets 34 for the fans 31 project toward the top of the partitions and blow the cool air toward and over the top of the partitions. The intakes 35 for the fans 32 extend parallel to the car floor and draw air from the car body below the false bottom 15 thereof and the outlets 34 for these fans 32 blow the air up through the bunkers so as to insure the circulation of the air past the ice.

By this arrangement the circulation of air through the bunkers and through the car body is insured, so that the rapid cooling of the foodstuffs in the car body will be had and so that the foodstuffs can be maintained at the desired low temperature.

My present invention resides more particularly in the novel means employed for operating the air circulating fans 30, 31 and 32 in a simple and economical manner. To bring about the operation of the fans, I provide a fluid circulating pump 37. This pump can consist of a cylinder 38 rigidly secured in any preferred manner to the car body. Mounted for reciprocatory movement within the cylinder is a piston 39 having connected therewith a piston rod 40. The end of the cylinder opposite to the end and which supports the piston rod, is provided with a one-way outlet check valve 41 and one-way inlet check valve 42. The inlet check valve 42 controls the flow of oil or other fluid into the pump 37 from a conduit pipe 43. This conduit pipe in turn communicates with an oil reservoir or like tank 44. The outlet check valve 41 controls the flow of oil under pressure from the pump to a conduit 45.

The pump 37 can be actuated in various manners from the car and one of my proposed methods is illustrated in Figures 1 and 2. As shown in these figures, the piston rod 40 is operatively connected to a pitman wheel 46 by means of a pitman rod 47. The wheel 46 is rotatably carried by a pivoted hanger arm 48, which is supported from the bottom of the car body. This pivoted hanger arm is normally urged downward by means of an expansion coil spring 49. The arm and pitman wheel is so hung that the pitman wheel normally engages one of the axles 21 so that the same will be rotated thereby, when the car is in transit, so that the pump will be actuated. The wheel 46 can be provided with any suitable friction surface so as to insure proper driving contact between the same and the axle.

The wheel and its supporting arm 48 can be pulled up against the tension of the coil spring 75.

49 so as to hold the wheel 46 from out of driving engagement with the axle when such may be desired. This can be accomplished by means of a latch rod 50 pivotally connected with the hanger arm and the latch rod can be provided with one or more notches 51 for receiving a keeper lug 52 formed on a hanger bracket 53 carried by the car body. This hanger bracket is provided with a spring for normally urging the latch rod 50 toward the keeper lug.

Each of the air circulating fans can be provided with a driving turbine 54, if so desired, and in that form of my invention shown in Figures 1 to 4, inclusive, I have shown a turbine 54 for each fan. These turbines are preferably arranged on the outside of the car so that the same will not occupy any space within the car body and each turbine is firmly united to the car by means of fastening elements 55. Each turbine includes a turbine casing 56, having rotatably mounted therein the turbine wheel 57. The periphery of the wheel carries any preferred type of buckets 58. Extending into each turbine casing is a nozzle 59 and the outlet of the nozzle is arranged substantially tangentially to the periphery of the turbine wheel. The feed pipe or conduit 45 connects (through suitable branches 61) with the nozzles 59 of each turbine, so that the turbines will be effectively driven. A suitable outlet 59 for the spent oil can be provided in each turbine casing at the desired advantageous point.

The hub of each turbine wheel is keyed to a drive shaft 60 and the hub of the fan wheel of an adjacent fan is keyed or otherwise secured thereto so that the fan wheel will be rapidly driven from its turbine.

The reservoir tank 44 has communicating therewith a return pipe 62 for the spent oil or other liquid and this pipe 62 has communicating therewith (by means of suitable branches) the outlets 59 of the turbines.

From the description so far, it can be seen that I have provided means for operating a series of advantageously actuated air circulating fans from turbines, which are in turn driven by oil or other fluid under pressure.

In Figure 5, I have shown a slightly modified form of my invention, and in this form I have shown a drive shaft 63 for a pair of transversely aligned air circulating fans instead of a single drive shaft for each fan. As is clearly illustrated in this figure, the shaft 63 can extend entirely across the car and the ends of the shaft can be keyed or otherwise secured directly to the hubs of the turbine wheels of the adjacent turbines.

In Figure 1, I have shown the air circulated in such a way that the air is sucked from below the bottom of the car body and forced up through the bunker and then drawn off of the top of the bunker and forced into the body of the car from over the transverse partitions. Obviously, the air can be circulated in the opposite direction, in which instance the air fans are driven in the opposite direction so as to reverse the intake and exhaust of air from the fan casings. This is clearly shown in Figure 7 of the drawings. Hence, the circulating fans 30 draw the air from the top of the car and blow the air in to the top of the bunkers over the partition 11. The top rear air circulating fans 31 blow the air downward into the bunkers toward the ice. The bottom fans 32 suck the air through the bunkers and blow the air under the grating 14 and under the car false bottom 15.

I have found that the oil pumps can be op-

erated efficiently from the various motions developed between the car body and its trucks, between parts of the trucks and between cars themselves.

In Figure 8, I have shown one way of operating pumps from the motion developed between the car body and its trucks. Usually there is a transverse sway between the car body and the trucks, and I utilize the sway of this body for operating the pumps. As shown in Figure 8, I provide a pair of pumps 65 and these pumps can be rigidly secured to the bottom of the car body 10. Each pump 65 includes a vertically disposed cylinder 66 having reciprocally mounted therein a piston 67 connected to a piston rod 68. The piston rods extend through the lower cylinder heads and the cylinders at one end are provided respectively with an intake check valve 69 and an outlet check valve 69'. The outlet check valve controls the flow of fluid to a feed pipe 70. The oil can be distributed from the pipe 70 to the various turbines in the same manner as shown in the first form of my invention. The inlet check valve controls the intake of oil for the return line or oil reservoir (not shown). Mounted intermediate their ends on the side frames 17 and 18 of the car trucks 16 for rocking movement, are operating levers 71. These levers 71 rock on the side frames 17 and 18 as a fulcrum and the levers can be either pivoted thereto as shown, or merely rest thereon for the desired rocking movement. The outward ends of the levers are operatively connected for swinging movement with brackets 72 bolted or otherwise secured to the lower ends of the top bolster 21. The inner ends of the levers are operatively connected, by means of pivot pins 73, with the outer ends of the piston rods 68.

It can be seen that as the car body sways on the car trucks, the levers 71 will be alternately raised and lowered and this will in turn impart the desired reciprocating movement to the piston 67.

In Figure 9 I have shown means for operating the pumps from the motion developed between parts of a car truck. In this form of my invention, the cylinders 75 of the pumps 76 are rigidly bolted to the bottom plank 25 of a car truck 16. The pumps are disposed on opposite sides of the center of the truck and each cylinder has reciprocally mounted therein a piston 77 connected to a piston rod 78. The piston rods 78 slidably extend through the upper cylinder heads of the cylinders. The opposite ends of the cylinders from the upper cylinder heads are provided with intake check valves 79 and outlet check valves 79' for the oil pipes 80. The feed and return of oil to the turbines is the same as shown in Figures 1, 2 and 3. In this form of my invention, I also provide rock levers 81 and these levers are pivotally mounted intermediate their ends for swinging movement on pivot pins 82 carried by the bolster 23 of a car truck. The pivot pins 82 are located on the opposite sides of the transverse center of the bolster and the inner ends of the lever are operatively connected to a pivot pin 83 carried by the bottom plank 25 of the car

truck. The outer ends of the levers are pivotally and operatively connected by means of pins 84 with the upper ends of the piston rods 78 of the pumps. Any movement between the bolster 23 and the plank 25 developed will cause the rocking of the levers 81, which in turn will bring about the reciprocation of the piston 77 and the delivery of oil to the turbines. As heretofore described, the bolster 23 is resiliently supported upon the plank 25 by coil springs 24 and consequently there is an up and down movement between the bolster and its supporting plank.

I have illustrated three preferred forms of my invention for operating the pumps and broadly the invention comprehends the making use of motion between a car body and its trucks, adjacent cars, or the motion between parts of a car truck for operating the pumps.

Any preferred means can be utilized for pre-cooling the car or driving the turbines while the car is standing still.

Changes in details may be made without departing from the spirit or the scope of this invention, but what I claim as new is:

- 25 In a refrigerator car of the type having a body, including a storage compartment and a bunker compartment therein, car trucks for the body including side frames, a resiliently supported bolster carried by the side frames, a top bolster secured to the car body and rockably supported to the first bolster, an air circulating fan for drawing air from one of said compartments and delivering it to the other of said compartments, means for operating said fan including a turbine, 30 a fluid pump delivering oil under pressure to said turbine for operating the same, means for securing the pump rigidly to the floor of the car between the side frames, rock levers fulcrumed on the side frames, means operatively connecting one end of the levers to the top bolster and means 35 operatively connecting the opposite ends of the levers to the pump.

ROBERT KENT SCHWEBs.
